UNITED STATES PATENT OFFICE.

JOSEPH R. B. NORFOLK, OF JESSUPS, MARYLAND.

CONTROL FOR ARTIFICIAL ARMS AND LEGS.

1,388,524.

Specification of Letters Patent. Patented Aug. 23, 1921.

Application filed August 18, 1920. Serial No. 404,479.

To all whom it may concern:

Be it known that I, JOSEPH R. B. NORFOLK, a citizen of the United States, residing at Jessups, in the county of Anne Arundel and State of Maryland, have invented 5 certain new and useful Improvements in Controls for Artificial Arms and Legs, of which the following is a specification.

My present invention relates to means for 10 controlling movements of artificial members such as arms and legs. Its principal objects are to improve the efficiency of such controls and to provide for greater comfort to the wearer of the artificial member under 15 certain conditions, and to do so by simple and readily operable means while maintaining the operative relation of the control in service to the artificial limb.

In the accompanying drawings, which 20 form a part of this specification, Figure 1 is a face view of end portions of two sections of a control strap or tape with an intermediate adjusting device in its control-lengthening condition; Fig. 2 is an edge 25 view of the parts of Fig. 1; Figs. 3 and 4 are views respectively similar to Figs. 1 and 2 but showing the connection device in its control-shortening position; Fig. 5 is a perspective of the swinging part of the connection device; and Fig. 6 shows one application 30 of the device to a control strap for an artificial leg.

As is well understood in the art, the movements of the artificial limb are often controlled by means of a strap, usually in the 35 form of a fabric tape, which is secured at one end to an operative part of the artificial member, the other end of the strap terminating in a loop which passes over the wearer's shoulder. The length of this control 40 strap is such that by lifting his shoulder the operator can draw firmly upon the strap or tape and provide motion which operates the leg or arm as the case may be. Illustrations of such controls and their general 45 mode of operation may be found in my Patent No. 1,293,885 of February 11, 1919 on artificial limbs, and in my allowed copending application, Serial No. 302,658 filed 50 June 9, 1919 on artificial legs.

In such controls an ordinary buckle is sometimes provided for adjusting its length to suit the general requirements of the particular wearer of the device. Adjustments 55 by means of the ordinary buckle may be made from time to time as occasion sug-

gests but such adjustments are intended to be of a substantially permanent character, and are not readily to be made without putting the artificial member temporarily out 60 of service. I have found that in certain situations, for instance in a leg device where the wearer is about to go upstairs, it is desirable to shorten the control materially so as to render the pull by the shoulder upon 65 the strap more firm and positive, through the taking up of temporarily induced slack, than is called for in the ordinary operation of walking, and these improvements have as a specific object the provision of a control 70 which may be readily and easily shortened and lengthened as required by particular exigencies of service, or for the comfort of the wearer, and without putting the artificial limb out of service. 75

In these drawings the end portion 10 of the control strap or tape is to be understood as leading to the shoulder loop mentioned while the fragment 11 thereof leads to the artificial member the movements of 80 which are to be controlled. To the strap part 10 I secure an eye member 12 consisting of a metallic plate having a slot-like opening at 13 through which the tape passes and is fastened upon itself as by stitching, 85 thereby holding the plate 12 securely at the end of the section 10 of the tape. To the section 11 of the tape is similarly secured the bow or yoke 14 having a pair of side members 15 apertured at 16 to form bearings for the pintles 17 of the swinging cam-like device 18. 90

This swinging or rocking member 18 includes the cross bar 19, the finger lever 20 and the loop-shaped part 21. The plate or 95 eye member 12 has a slot-like opening or eye 23 through which the loop-shaped part 21 passes. The two tape ends 10 and 11 are therefore joined and the control made continuous by this intermediate adjusting device comprising the plate 12, the swinging member 18 and the yoke member 14. 100

From the edge views it will be clearly seen that the distance from the axis of rocking movement of the part 18, namely, the axis defined by the pintles 17, to the ends respectively of the loop part 21 differs. When the parts are in their relative positions as shown by Figs. 1 and 2 what may be termed the long end portion of the loop 21 is interposed 110 between the eye 23 and the axis of rocking movement defined by the pintles 17. When

the finger piece 20 is swung downward into the position shown by Figs. 3 and 4 the short end portion of the loop 21 is between the eye 23 and the axis of rocking movement, and 5 the effective length of the control is therefore materially shortened when the parts are in the relative positions of Figs. 3 and 4 as compared with Figs. 1 and 2.

While the control strap is ordinarily under the shirt of the wearer it is a simple and easy matter for him to operate the finger piece 20 through the shirt, and according to these improvements he is therefore enabled to increase and decrease the effective length 15 of the control for particular movements from time to time or, should he find that owing to conditions of adjustment of the stump in the socket of the artificial member the control is effectively too long or too short 20 for comfort, an adjustment may be made with the device of these improvements until an opportunity offers for making the more permanent adjustment desired, which can be done by the ordinary buckle hereinabove 25 referred to where the device is provided with that feature.

In my practice the parts 12, 14 and 18 are of metal. The strap or tape portions may be of the usual construction.

30 While I have herein illustrated and described a simple and advantageous form of my novel control reference should be had to

the appended claims to determine the scope of the improvements herein set forth.

I claim:

1. In a control for artificial limbs, the combination with control strap sections, of an intermediate device for readily increasing and decreasing the effective length of the control while maintaining the operative relation of the control in service to the artificial limb. 35

2. In a control for artificial limbs, the combination with control strap sections, of an intermediate device including a hand-operable movable member for readily increasing and decreasing the effective length of the control while maintaining the operative relation of the control in service to the artificial limb. 45

3. In a control for artificial limbs, the combination with two control strap sections, of an eye member secured to one section, a yoke member secured to the other section, and a rocking member mounted on the yoke member, said rocking member including a loop part passing through the eye of the eye member, said loop part having a relatively long end portion and a relatively short end portion with respect to the axis of rocking 55 movement. 60

JOSEPH R. B. NORFOLK.
